UNITED STATES PATENT OFFICE.

SAMUEL A. KORNSWEET, OF LOS ANGELES, CALIFORNIA.

TELEPHONE ATTACHMENT.

Application filed June 16, 1924. Serial No. 720,236.

This invention relates to an attachment on the receiver of a telephone to facilitate use thereof.

An object of the invention is to provide an attachment that will support the receiver when the attachment is placed on the desk and that will be supported by the receiver when the receiver is hung on the switch hook, said attachment having an auxiliary earpiece.

Another object is to provide an attachment of this character that will enable the telephone receiver to be connected with the ear of a stenographer or other person so that such person may take down on the typewriter that portion of the conversation that comes from the distant station. Thus, one of the parties to the conversation over the telephone can, while conversing, have his secretary or stenographer "listen in" and make notes.

Other objects and advantages will appear hereinafter:

The accompanying drawings illustrate the invention:

Figure 1 is a perspective view showing a telephone attachment embodying the invention and connected with a telephone instrument.

Fig. 2 is an elevation, mainly in midsection, showing the telephone receiver and an earpiece and the connecting means therefor, the flexible extension tube being omitted and the plug being in place.

Fig. 3 is a plan view, partly in section, from the line indicated by 3-3, Fig. 2.

Fig. 4 is a plan view of the pedestal base, the standard being shown in section and the receiver clamping plate being omitted.

Fig. 5 is a view, mainly in midsection, of the extension earpiece.

Fig. 6 is an enlarged detail, partly in section, of the upper portion of the standard, a fragment of the extension tube also being shown and the coupling that connects it with the standard.

Fig. 7 is a longitudinal view of the plug employed to close the port with which the extension tubing connects.

An ordinary telephone receiver is indi-

cated at 11 and, when not in use, it is suspended in the usual manner from the switch hook 12 of the telephone instrument indicated in general by the character 13. The instrument illustrated is of the desk type. I provide an auxiliary earpiece 14 and a connection 15 between the receiver 11 and earpiece 14. This connection 15 is of a construction that can be set on a table, desk, or other suitable support and, when so set, will support the receiver 11, and is also of a type that will itself be supported by the receiver 11 when said receiver is suspended from the switch hook 12.

The particular construction of the connection 15 that I employ at present is as follows:

A flat bottom base 16 is provided in its upper face with a recess 17 to accommodate the cap 18 of the receiver 11. Suitable means are provided to hold the cap 18 in the recess and, in this instance, a circular sectional plate 19 is secured by screws 20 to the upper face of the base 16 in position to overlap the marginal portion of the cap 18. Preferably an annular gasket 21 of rubber or other suitable material, is positioned between the cap 18 and plate 19. The plate 19 is split so that the sections thereof may be readily assembled in place around the receiver 11 after the receiver cap is inserted in the recess.

Preferably, the bottom of the recess 17 is provided with a gasket 22 of rubber, or other suitable material, to effectually seal the joint between the base 16 and receiver cap 18. The gasket 22 surrounds a tubular portion 23 that projects upwardly from the bottom of the recess 17 into the opening 24 in the receiver cap 18, said opening 24 being that through which the sound waves pass out of the receiver. The upper end of the tubular portion 23 approximately fits the opening 24. The tubular portion 23 forms a vertical portion of a duct of which a horizontal portion is indicated at 25, said duct being formed in the base 16.

Communicating with the duct 25 is a tubular standard preferably comprising two sections, a lower section 26 screw threaded into

the base 16 and an upper adjustable section 27 slidably engaging the section 26, the two sections being in telescopic relation. To hold the section 27 in adjusted position any suitable means may be employed and, in this instance, for this purpose a set screw 28 is mounted in the section 26 and releasably engages the section 27. The section 27 is of angular construction, the upper portion thereof forming a horizontal arm 29 which has an internally threaded port 30 at its rear end to receive either a screw threaded plug 31, as in Fig. 2, or the screw threaded coupling 32 on one end of a flexible extension tube 33, as in Figs. 1 and 6.

The other end of the tube 33 is provided with an ear piece 34 which may be held in place on the head by a spring clamping member 35 of a construction commonly employed for holding a telephone receiver against the ear. The forward end of the arm 29 is provided with the receiver 14, previously mentioned.

The invention operates as follows:

Let it be assumed that the receiver 11 is suspended from the switch hook 12 as in Fig. 1. As is readily understood, this is the position of the receiver when the telephone is not in use. In this position of the receiver 11, the auxiliary earpiece 14 and the connection means 15 are supported by the receiver 11. To use the telephone the receiver 11 will be removed from the switch hook 12, as is customary, and the base 16 will be seated on the desk or table that supports the telephone instrument. The person telephoning will position himself so that his ear will be adjacent to the earpiece 14 with the telephone transmitter opposite to his mouth. This will enable him to hold conversation over the telephone without the necessity of holding the receiver 11 to his ear.

If the person telephoning desires to have recorded the words of the party speaking to him, he will call his secretary or stenographer who will clamp the ear piece 34 to her ear, thus enabling her to hear the words issuing from the receiver 11. The secretary or stenographer will thus be enabled to employ her hands in operating a typewriter, while "listening in" on the telephone and at the same time the person telephoning will be enabled to hear all that is said and reply, when necessary, to the party at the other end of the line.

When it is not desired to employ the ear piece 34, the coupling 32 will be disconnected from the arm 29 and the plug 31 will be substituted therefor, as in Fig. 2. The earpiece 14 will be adjusted to a convenient height by loosening the set screw 28 and sliding the section 27 in or out and then tightening said screw.

From the foregoing it will be clear that the attachment can be connected with an or-

dinary desk telephone set without the exercise of any great degree of skill, since all that is necessary is to detach the plate 19, insert the receiver 11 in the recess and then attach said plate 19 so as to hold the receiver in place in the base 16.

I claim:

1. A telephone attachment comprising a base having a flat bottom adapted to rest on a supporting surface, the base having a recess in its upper face and having a duct communicating with said recess, a tubular standard secured at its lower end to the base and communicating with the duct, an earpiece on the upper end of the standard communicating with the bore of the standard, and means to clamp the cap of a standard telephone receiver in the recess so as to support such standard receiver in vertical position on the base.

2. A telephone attachment comprising a base having a flat bottom adapted to rest on a supporting surface, the base having a recess in its upper face and having a duct communicating with said recess, a tubular standard secured at its lower end to the base and communicating with the duct, the upper portion of the standard forming a horizontal arm, and an earpiece secured to the horizontal arm and communicating with the bore thereof.

3. A telephone attachment comprising a base having a flat bottom adapted to rest on a supporting surface, the base having a recess in its upper face and having a duct communicating with said recess, a tubular standard secured at its lower end to the base and communicating with the duct, the upper portion of the standard forming a horizontal arm, an earpiece secured to one end of the horizontal arm and communicating with the bore thereof, a flexible tube coupled at one end to the other end of the horizontal arm and communicating with the bore thereof, and an earpiece on the other end of the flexible tube.

4. A telephone attachment comprising a base having a recess to accommodate the cap of a standard telephone receiver, a circular sectional plate surrounding the receiver and secured to the base and projecting over the margin of the recess to hold the cap in the recess, the base having a duct communicating with the recess, a tubular standard secured at its lower end to the base and communicating with the duct, and an earpiece secured to the upper end of the standard and communicating with the bore thereof.

5. The combination with a desk telephone, of a base secured to the telephone receiver and provided with a duct communicating with the mouth of said receiver, the base provided with a flat bottom adapted to rest on a supporting surface when the receiver

- is off of the switch hook of the telephone, said base being entirely supported by the receiver when the receiver is in place on the switch hook, a tubular standard secured at its lower end to the base and communicating with the duct and projecting above the level of the switch hook when the base is supported by the receiver on said hook, and an earpiece secured to the upper end of the standard and communicating with the bore thereof. 10
- 5 Signed at Los Angeles, California this 9 day of June 1924.

SAMUEL A. KORNSWEET.
